UNITED STATES PATENT OFFICE.

WILLIAM W. DITTMAR, OF WILLIAMSPORT, PENNSYLVANIA.

PEW.

1,149,559.

Specification of Letters Patent.

Patented Aug. 10, 1915.

Application filed March 20, 1912. Serial No. 685,088.

To all whom it may concern:

Be it known that I, WILLIAM W. DITTMAR, a citizen of the United States, residing at Williamsport, county of Lycoming, State of Pennsylvania, have invented certain new and useful Improvements in Pews, of which the following is a specification, reference being had therein to the accompanying drawing.

10 This invention relates to certain new and useful improvements in church pews and more particularly to that class of pews which are curved longitudinally assuming the arc of a circle, the object being to improve the general construction of this class 15 of pew whereby the same can be manufactured at a less expense and at the same time have many advantages.

20 The main object of the invention is to provide a pew in which the seat and back, when placed in position within the end pieces, will be at an equal distance throughout its entire length from the base line and the back which is formed with a single or a 25 compound curve will have the convex portion at an equal distance from the top of the seat throughout its length.

20 In pews of this character now in use, the curved seat is secured to the back in such 30 a manner that it is necessary to trim the end portions of the back in order to provide a seat having a back of equal height throughout its length and to obtain the necessary or desired tilt to the seat, the back 35 and seat after being formed are tilted when placed in position within the end pieces whereby the end portions of the curved seat are thrown upwardly at a greater height from the base or floor than the central portion 40 of the seat. I obviate all of these difficulties by forming the seat dished in order to maintain an equal height from the base line and by forming the single or compound curved back on a form of such shape that 45 the upper portion is constructed on a greater radius than the lower portion, the convex portion will be maintained at an equal distance from the upper face of the seat in order to fit the back of a person sitting 50 therein.

55 In the drawings—Figure 1 is a perspective view showing a portion of a pew constructed in accordance with my invention; Fig. 2 is a transverse section through the same; Fig. 3 is a detail perspective view of a portion of a seat constructed in accordance

with my invention; Fig. 4 is a transverse section through a seat showing the manner of forming the same dished by arranging sections from which it is formed in stepped relation to each other; Fig. 5 is a section through a circular pew constructed in the ordinary manner now in use; Fig. 6 is a section through a circular pew constructed in accordance with my invention showing the dish to the bottom; Fig. 7 is a perspective view of a portion of a back constructed in the ordinary manner; Fig. 7^a is a section through the form on which the back, as shown in Fig. 7, is formed; Fig. 8 is a perspective view of the back constructed in accordance with my invention; Fig. 8^a is a section through a form upon which the construction of back, shown in Fig. 8, is formed; Fig. 9 is a front elevation of a portion of pew constructed in the ordinary manner showing the seat at a greater height from the base at the ends than at the center; and Fig. 10 is a front view showing a seat constructed in accordance with my invention whereby the seat is maintained at an equal distance from the base throughout its length.

Like numerals of reference refer to like parts in the several figures of the drawings.

5 In the drawings, 1 indicates the seat and 2 the back of my improved construction of 35 pew, the end pieces being omitted as they are formed in the usual manner. The seat 1 is curved longitudinally and is formed of a plurality of sections or strips 3 secured together by any suitable adhesive material in stepped relation as shown in Fig. 4 in order to obtain the desired dish to the seat as shown in Fig. 3 and after the seat is thus formed, it is shaped as shown by dotted 90 lines in Fig. 4 to form the convex portion 4 and the concave portion 5 on its upper face and a straight portion 7 on its under face. If a seat constructed in this manner was carried out to form a complete circle and a 100 transverse section taken through the same, it would assume the position shown in Fig. 6, that is, a dish would be formed so that the seat throughout its entire length would be at an equal distance from a horizontal or base 105 line. The manner of forming seats of this character now in use is shown in Fig. 5 and when the same is tilted, the outer end portions are thrown at a greater distance from the base line than the central portion.

110 The laminated back 2 is curved both vertically and longitudinally and is preferably

formed five-ply which is bent vertically to assume a single or a compound curve upon a form 30 as shown in Fig. 8^a before the adhesive material employed for securing the plies together has hardened and it will be seen that the back has an upper portion struck on a greater radius than the lower portion which will give the desired tilt to the back without actually tilting the same, thereby saving the material from which it is formed as it is not necessary to trim the end portions as is the case with a back constructed as shown in Fig. 7 when used in connection with a seat as shown in Fig. 5. 15 The compound curve of the back forms a convex portion 9 which will be maintained at an equal distance throughout its length from the top of the seat when the back is secured in position thereon and for securing 20 the back to the seat, I employ fastening members 10 over which is arranged a facing strip 11, the upper edge of the back also being provided with a facing strip 13 as clearly shown in Figs. 1 and 2. After the 25 back and seat have been secured together in this manner, they are ready to be placed in the end pieces and as shown in Figs. 1 and 2, it is not necessary to tilt the back and seat as the desired dish has already been obtained, thereby saving a great deal of time 30 in setting up a pew constructed in this manner.

The old form of seat 14 as shown in Fig. 5 cannot be set into the end pieces so that 35 the same will be maintained at an equal distance from the base line throughout its length as it will assume the position shown at 15 in Fig. 9; while in Fig. 10, I have illustrated the position a seat constructed in accordance with my invention will assume so 40 as to be an equal distance from the base line throughout its length. In Fig. 7, I have shown a back 16 constructed on a form 31 as

shown in Fig. 7^a in the manner now in use whereby it is necessary to tilt the same, 45 while in Fig. 8, I have shown a back constructed in accordance with my invention, showing that the same is built with the desired tilt.

From the foregoing description, it will be 50 seen that I have constructed a pew formed of a seat and back built with the desired inclination so as to conform to a person's back. It will also be seen that I have overcome the difficulties with pews curved longitudinally 55 by constructing a pew in which the seat is at an equal distance from the base line throughout its length and in which the convex portion of the back is at an equal distance from the upper ends of the seat throughout its 60 length.

What I claim is—

1. A longitudinally curved pew having a dished seat, with the front and rear edges thereof disposed in different horizontal 65 planes at equal distances throughout their lengths from the base.

2. As a new article of manufacture, a pew having a longitudinally curved dished seat with the entire front and rear edges thereof 70 for their entire length, disposed in different horizontal planes, and a longitudinally curved back with its top and bottom edges in two different vertical planes.

3. A church pew, formed of a longitudinally 75 curved seat and a longitudinally curved back of the same width throughout their lengths, said seat having its front and rear edges throughout their lengths, disposed in different horizontal planes.

In testimony whereof I affix my signature in presence of two witnesses.

WILLIAM W. DITTMAR.
